UNITED STATES PATENT OFFICE.

GEORGE WESLIN RYNDERS, OF CARPENTERSVILLE, ILLINOIS.

WASHING MACHINE.

Application filed March 2, 1925. Serial No. 12,666.

My invention relates to improvements in washing machines, and it consists in the combinations, constructions, and arrangements herein described and claimed.

5 An object of my invention is to provide a washing machine in which a plurality of washing operations may be carried on simultaneously and within the same container.

10 A further object of my invention is to provide a washing machine in which the washing operation simulates a hand washing operation in which the article is first removed from the water, is then squeezed slightly so as to remove the water therefrom, and is then plunged back into the water, this operation being repeated until the article is clean.

15 A further object of my invention is to provide a washing machine in which the clothes are held above the washing water which has become dirty whereby the clothes are not contaminated by this water.

20 A further object of my invention is to provide a washing machine in which the clothes container may be removed entirely from the water and then revolved at a high speed so as to dry the clothes by driving the water from the clothes by centrifugal force.

25 A further object of my invention is to provide a washing machine in which the containers are so connected to the operating mechanism that they will be automatically released from the operating mechanism when a person grasps any one of the containers.

30 A further object of my invention is to provide a washing machine in which the working parts of the washing machine may be removed and set out in the sun so as to thoroughly cleanse these parts.

35 Other objects and advantages will appear in the following specification, and the novel features of the invention will be particularly pointed out in the appended claims.

40 My invention is illustrated in the accompanying drawings, forming a part of this application, in which—

45 Figure 1 is a vertical section through the device, portions of it being shown in elevation,

50 Figure 2 is a plan view of the device with the cover removed,

55 Figure 3 is a section along the line 3—3 of Figure 1,

Figure 4 is a section along the line 4—4 of Figure 1,

Figure 5 is a section along the line 5—5 of Figure 4,

Figure 6 is a section along the line 6—6 of Figure 4,

Figure 7 is a section along the line 7—7 of Figure 2, and

Figure 8 is a section along the line 8—8 of Figure 2.

In carrying out my invention I provide a washing machine comprising a casing 1 having a cover 2 removably disposed on said casing. The casing 1 is mounted upon a carriage 3, the carriage in turn consisting of uprights 4 and a base 5. The base is mounted upon wheels 6 in the present device whereby the washing machine may be moved to any place desired.

In Figure 1, I show the uprights 4 as supporting a platform 7 upon which the casing 1 is disposed. The platform 7 has lugs 8 that are adapted to straddle drain pipes 9 carried by the casing 1. The lugs prevent the casing 1 from rotating with respect to the platform 7.

In the present device the casing is divided into three compartments in which a different washing operation may be carried on. Partitions 10 extend radially from the center of the casing and are notched at 11 adjacent to their upper edges. These notches permit the water to flow from one compartment to another so as to prevent the overflowing of the water onto the floor in case any one of the receptacles accidentally receives too much fluid. A clothes container 12 is mounted in each compartment and the washing machine is provided with novel means for rotating these clothes containers, for moving the containers up and down, for rotating the containers at a high speed when the containers are raised out of the washing water, and for raising the containers still higher when it is desired to remove the clothes from the containers or to move the containers into another compartment.

I will first describe the means for rotating the containers within the casing 1. Figures 1 and 3 show a motor 13 connected to a vertical driving shaft 14 by means of a gear train 15. The gear train 15 consists of two sets of two gears 16 and 17 and a clutch mechanism 18 for connecting the shaft 19 of the motor to either the set of gears 16 or 17. It is obvious that when the key 20 connects the gear 16 to the shaft 19, the shaft 14

will be rotated at a slow speed. If the key 20 connects the gear 17 with the shaft 19, the shaft 14 will be rotated at a higher speed.

In Figure 1, I show the shaft 14 as extending up into a container carrying member 21. The shaft 14 is made square at 22 from a point 23 on up to the top of the shaft. The container supporting member 21 is mounted upon a sleeve 24 that is adapted to raise the member 21 by means hereinafter described. The member 21 is adapted to be rotated with respect to the sleeve 24 and to be locked in adjusted position by means hereinafter described.

The member 21 has three arms which extend into the washing compartments. In Figure 8, I clearly show the container actuating mechanism mounted within each arm. The square portion 22 of the shaft 14 receives a sleeve 25 having a square bore 26. The sleeve 25 carries a beveled gear 27 adjacent to its upper end, this gear being in mesh with three beveled gears 28. Each of the beveled gears 28 is connected to a shaft 29, see Figure 8, by means of a flexible shaft 30. The lower end of the shaft 29 is rigidly connected to a disc 31 which has a conical shaped upper surface 32. A tubular member 33 is rotatably carried by the arm 34 of the member 21 and is held in frictional engagement with the disc 31 by means of a spring 35. The container 12 has a conical shaped portion 36, see Figure 1, that overlies the conical shaped portion 37 of the tubular member 33. The conical shaped portion 36 is secured to the portion 37 and is rotated when the portion 37 is rotated.

Assume now that the operator places his hand upon the container 12 while the container is rotating. The container will tend to come to a stop and of course this cannot happen unless the container is disconnected from the driving shaft 29. The container is automatically disconnected from the disc 31 due to spring 35 which permits the disc 31 to slip with respect to the conical shaped portion 37 when the container is held against rotation. In this way I provide a simple automatic means for disconnecting the container from the actuating means.

It will be seen from the foregoing that I have shown an operative means for connecting the motor 13 with each of the three containers 12. When the containers 12 are in their lowermost position, as shown in Figure 1, the gear 16 is connected with the shaft 19 and therefore rotates the containers at a slow speed. It is not desirable to rotate the containers at a higher speed because this will cause the water to whirl so as to make it almost impossible for it to enter through the openings in the perforated container. If, however, the containers are raised into the dotted line position shown at 38 in Figure 1, the containers are raised free of the water.

and may now be rotated at a higher speed than formerly so as to cause the water to leave the clothes due to centrifugal force. In this way I provide a simple drying means for the clothes which is adapted to dry the clothes to the same extent as does a wringer. In this way the wringer may be done away with and therefore obviates this extra operation which is necessary in the usual washing machine.

The means for raising the containers 12 into the dotted line position shown at 38 will now be described. This means is adapted to raise and lower the containers from the full line position into the dotted line position while the containers are being rotated. In Figure 1, I show the sleeve 24 as being keyed to the casing 1 at 39, the sleeve being provided with a groove 40 so as to permit the sleeve to be raised and lowered with respect to the casing 1. The sleeve is provided with a pin 41 at its lower end, this pin being adapted to raise and lower the sleeve with respect to the casing when the pin is moved by means now to be described. The pin is slidably received within a slot 42 of a link 43. The link in turn is pivotally secured to two arms 44 and 45 that in turn are pivotally mounted upon brackets 46 and 47. In Figure 1 I show the brackets as being secured to the platform 7.

The link 43 is rocked by means of the arms 44 and 45 whereby the link will be raised and lowered slightly so as to impart a vertical movement to the sleeve 24 through the medium of the pin 41. The rocking means is shown in Figures 1, 3, 4 and 5. It will be noted in Figure 3 that one of the gears 16 carries a rack 48 which is pivotally secured to the gear 16 at 49. The rack in turn is held in mesh with a gear 50 so as to oscillate the gear 50 while the gear 16 is rotating. The gear 50 in turn is rigidly secured to the hub 51 of the arm 45 whereby a rocking or oscillation of the gear 50 will swing the arm 45 from a vertical position into the full line position shown in Figure 5. Since the arm 45 is connected with the arm 44, the arm 44 will also be swung with the arm 45.

As heretofore stated, the rocking of the arms 44 and 45 will raise and lower the sleeve 24. The sleeve in turn carries the container supporting member 21 and will therefore raise and lower the member 21 so as to lift the containers 12 into the dotted line position 38 and then lower them into the full line position (see Figure 1). The water line of the casing 1 is directly below the bottom of the containers 12 when the containers are raised into the dotted line position 38. I have shown the water line by means of a broken line 52.

When the containers are raised into the dotted line position 38 by another means now

to be described, the operator may disconnect the container lifting means just described, and throw the clutch 18 so as to increase the speed of the containers whereby the water will be driven from the clothes by centrifugal force. The operator in raising the containers into the dotted line position 38 so as to hold the containers in this position, grasps the actuating handle shown in Figure 1, and swings it into the dotted line position 54.

Figures 4 and 5 clearly show how the handle 53 moves the rack 48 out of engagement with the gear 50, and Figure 1 shows how the handle swings the containers into the dotted line position 38.

A bracket 55 slidably receives the rack 48 and normally holds the rack in engagement with the gear 50. In Figure 5, I clearly show how the bracket 55 is provided with a slot 56 which slidably receives the end of the handle 53. A spring 57 is disposed in the slot 56 and yieldingly holds the rack 48 in engagement with the gear 50. It will also be noted in Figure 5 that the bracket 55 has a flange 58. An arm 59 is rigidly secured to the handle 53 and is swung into contact with the flange 58 when the handle 53 is swung into the dotted line position 54 shown in Figure 1. The arm 59 is long enough to swing the bracket 55 away from the gear 50, this movement compressing the spring 57. The bracket 55 in moving away from the gear 50 carries with it the rack 48 and therefore disengages the rack from the gear 50. It will now be seen that further movement of the rack 48 will not move the gear 50.

The handle 53 when swung into the dotted line position 54 not only disconnects the rack 48 from the gear 50 but also swings the arms 44 and 45 into the dotted line position 44' and 45'. This movement of course raises the link 43 and therefore lifts the containers 12 free of the water within the casing 1. The operator may now actuate the clutch 18 so as to connect the gear 17 with the shaft 19 whereupon the containers 12 will be actuated at a much higher speed than they formerly were. This speed is sufficient to cause the water to be driven from the clothes by centrifugal force.

I stated in the first part of the specification that a different washing operation may be carried on in each compartment. Assume that in the present instance one of the containers is washing the clothes in soap suds, a second container is rinsing the clothes in clear water, and a third container is blueing the clothes, and the operator wishes to move the containers so as to have the container formerly washing the clothes in soap suds, rinse the clothes in the clear water compartment. To do this the operator may swing the handle 53 from the dotted line position 54 into the dotted line position 54' (see Figure 1).

This movement still holds the rack 48 out of engagement with the gear 50 due to the fact that the arm 59 still contacts with the flange 58. This movement also swings the arms 44 and 45 into the dotted line position 44'' and 45''. The arms, of course, carry the link 43 therewith, the link in turn lifting the sleeve to a still higher position so as to raise the containers 12 into the dotted line position 38'. The bottoms of the containers 12 are now disposed above the top of the casing 1. The containers are held in the positions 38 and 38' by the operator keeping hold of the handle 53. The operator may swing the containers into the next adjoining compartment upon releasing a locking mechanism now to be described.

The locking means is a simple device and is clearly shown in Figure 7. The container carrying member 21 has a bore 60 therein that extends radially from the center of the member 21. The bore 60 is adapted to be aligned with any one of three openings 61 in the sleeve 24. A spring 62 yieldingly holds a pin 63 in the opening 61 whereby the container supporting member 21 is locked to the sleeve 24. As heretofore stated, the containers 12 may be raised into the dotted line position 38' and may then be swung with respect to the casing 1 so as to align the containers with the next adjacent compartment if desired. Before the member 21 can be moved so as to swing the containers from one compartment to another, the pin 63 must first be manually removed from the opening 61 in which it is disposed. As soon as the pin 63 is removed from the opening 61, it will bear against the outer surface of the sleeve 24 and will drop into the next opening as soon as the member 21 has been swung a sufficient distance to align the pin with the opening. In this way the operator may change the clothes from one washing operation to another without first having to remove the clothes from the container. Stops 64 are carried by the bracket 46 and prevent the link 43 from moving beyond the dotted line position 43'' shown in Figure 1.

It will be noted that although the arms 44 and 45 are normally swung by the rack and gear mechanism, the arm 45 may be raised into the dotted line position 45' and 45'' by means of the handle 53. Of course, the arm 44 is moved when the arm 45 is moved. The means for moving the arm 45 comprises a disc 65 that has a notch 66 therein. The arm 45 has a projection 67 that is engaged by the notch 66 when the handle 53 is swung into either of the dotted line positions 54 and 54'. I have notched the disc 65 in this manner so as to permit the arm 45 to function in a normal manner.

From the foregoing description of the various parts of the device the operation thereof may be readily understood. When washing

the clothes the compartments are filled with water approximately to the line 52 shown in Figure 1. The handle 53 is then swung so as to raise the containers 12 into the dotted line position 38'. The clothes may now be placed within the containers and the containers then moved down into the compartments. As shown in Figure 1, the containers are smooth and are rounded so as to prevent the clothes from being caught and torn during the operation of the machine. The clutch is now actuated so as to connect the gear 16 with the shaft 19, whereupon the device will be rotated at a slow speed. The gears 16 not only cause the containers 12 to rotate, but also cause the rack 48 to actuate the arms 44 and 45 so as to raise and lower the containers out of and into the water. As heretofore stated, the best washing operation possible is to raise the clothes out of the water, compress the clothes slightly, and then again submerge the clothes in the water. The washing machine follows this operation as closely as possible in that it raises the clothes out of the water and, due to the rotation of the containers, causes the clothes to compress slightly from centrifugal force, thus squeezing a portion of the water therefrom, and then again submerges the clothes in the water. Furthermore the washing operation creates a partial vacuum within each compartment, this being due to the fact the container in each compartment is suddenly raised which causes the conical shaped portion 36 of each container to create a suction and draw the water upwardly with the movement of the container. On the upward stroke therefore the water rushes down on the outside of each container, due to the suction of the conical shaped portion 36, and during this movement the container is revolved so as to drive the water out of the clothes by a slight centrifugal force. On the downward stroke the clothes are sprayed by fine jets of water that rush through the openings in the container and up through the openings in the conical shaped portion 36. Of course, some of the water is also forced up along the outside of the containers and this water overflows into the container and thus prevents the clothes from floating out of the container. The force of the jets of water upon the clothes and the force of the water that comes pouring over the open top of each container imparts a slight rolling and turning movement to the clothes within the container.

After the clothes are washed, the containers may be raised to a position above the water level, and this is done by means of the handle 53. The containers are now free of the water and may be revolved at a high speed when the clutch 18 is actuated so as to shift the gears into high speed. An R. P. M. of five hundred is best adapted for the dry-

ing operation, although any other speed desired may be used without departing from the spirit and scope of my invention.

After the clothes are dried, the handle 53 may be swung into the dotted line position 54' so as to cause the bottoms of the containers to clear the partition walls 10. If three operations have been carried on, that is, the soaping, rinsing and blueing operations, the clothes from the container that have been in the blueing water may be removed and a new batch of soiled clothes substituted therefor. The containers may now be swung so as to dispose the container having the soiled clothes in the compartment containing the soap suds. This movement, of course, will move the other containers to the next adjacent compartment whereby the washing machine may again be operated. Of course, the locking mechanism shown in Figure 7 is operated to permit the containers to be moved from one compartment to the next.

A point to be borne in mind is the fact that the operator never places his hands in hot water during the entire washing operation. This, of course, reduces hazards of injury from pins and the like in the clothes to a minimum. After the operator has placed the soiled clothes in the container it is unnecessary for him to again touch the clothes until they have been thoroughly washed, rinsed, blued and dried. A further point to bear in mind is the fact that the clothes are aerated while the containers are being rotated above the water level. It will therefore be seen that the clothes are thoroughly cleansed by the washing operation as well as by the airing of the clothes during the washing operation. As heretofore stated, the machine does away with the use of wringers and therefore very fragile clothing may be handled by the machine. In fact different classes of clothes may be washed at the same time, because each class is washed in a separate compartment. Another novel feature of the device lies in the fact that the containers 12 are so connected to the actuating mechanism that they will be automatically disconnected from the actuating mechanism when they are touched by the hand of the operator. This is another point which cuts down the chances of injury to a minimum.

As stated in the first part of the specification, the container carrying member 21 may be removed from the casing 1, and will of course carry with it the containers 12. This part of the mechanism may be placed in the sun where it will be thoroughly cleansed. It is a known fact that washing machines after use for a short time become rancid and give forth an odor which is obnoxious. In the washing machine shown in the accompanying drawing, I provide means whereby the working parts

may be entirely removed from the machine so that these parts may be cleansed. Furthermore the casing 1 is provided with rounded corners so as to permit the casing 5 to be easily cleaned. In Figure 8 I also show an oil pocket 67 which is adapted to feed oil to the sleeve 24 whereby the machine will operate efficiently. This construction also prevents any oil from seeping into the washing compartments.

It is obvious that the containers 12 may be altered in shape slightly so as to carry dishes or other articles whereby the machine will be able to wash these articles just 15 as effectively as it washes clothes.

I claim:

1. In a washing machine, a carrying member, a sleeve for supporting said carrying member, means for raising and lowering 20 said sleeve so as to raise and lower said carrying member, and manually controlled means for disconnecting said first named means from said sleeve and for raising said carrying member, containers carried by said 25 carrying member and raised above the level of the washing fluid when said manually controlled means is actuated, and means for rotating said containers at a high speed when said containers are in their raised position.

2. A washing machine comprising a compartment adapted to carry water, a container disposed within said compartment, a supporting member for holding 35 the container above the bottom of the compartment, means for revolving said container, means for automatically raising and lowering said supporting member so as to raise the container above the water and lower the container into the water within said 40 compartment, and manually controlled means for disconnecting said container-raising means and for raising the supporting member whereby said container is lifted

clear of the water, said manually controlled means being movable still further so as to lift the container clear of the top of said compartment.

3. A washing machine comprising a casing having a plurality of compartments 50 therein, a clothes container disposed in each compartment, a carrying member for supporting said clothes containers, power means, means connected to said power means for revolving said containers, means connected to 55 said power means for raising and lowering said carrying member so as to lift the containers clear of the water within the compartments and to again submerge the containers in the water, and manually power elevating 60 means for lifting the carrying member so as to lift the containers clear of the water, this means also being adapted to disconnect said means for raising and lowering said 65 container supporting member, the containers rotating at a higher speed when said containers are lifted free of the water, said manually controlled means being movable still further so as to lift the containers above the tops of the compartments.

4. In a device of the type described, a supporting member, a container carried by said member, means for rotating said member, said means including a spring-actuated clutch, whereby said member is automatically disconnected from said rotating means when said container is held against movement.

5. In a device of the type described, a supporting member, a container carried by said member, a driving shaft, a disk rotated by said driving shaft, spring means for causing said disc to frictionally engage with said member to rotate said member, said spring means permitting a disengagement of said disc from said member when said container is held against rotation.

GEORGE WESLIN RYNDERS.
